CUPOLA APPARATUS AND METHOD OF
MELTING METAL

Herbert A. Reece, Cleveland Heights, Ohio

Application March 13, 1942, Serial No. 434,455

13 Claims. (Cl. 266—25)

My invention relates to metallurgical furnaces and particularly to cupolas in the foundry art and to similar devices.

The efficient and economical operation of a foundry often requires that cupolas of different melting capacity be used at different times in accordance with the requirements of the foundry. Where there is a large sized cupola and the foundry requirements call for a relatively small amount of metal to be melted it is necessary to operate the cupola on the basis of a charge proportioned to a cross-section of the cupola with resulting dilution of charges and excess costs for metal produced.

In the past it has often been the custom to attempt to proportion the cupola in accordance with the amount of material to be processed by re-building the walls of the cupola with a thicker lining to decrease the internal diameter of the cupola. This system of re-building the cupola to change its melting capacity in accordance with the amount of metal to be melted has serious disadvantages and limitations. It is necessary to clean out the cupola completely, to cool it, and to re-build the refractory lining of the well or lower portion of the cupola. Such a system is laborious, expensive and time consuming.

Another possible way of meeting the requirements of a foundry is to have a plurality of complete cupolas, each of a different size or melting capacity. The cupola having the desired capacity for the requirements of the foundry at any one time is operated and the other cupolas remain idle. The disadvantages and limitations of this answer to the problem are also apparent. The cost of having a plurality of cupolas available when only one is to be operated is often a prohibitive expense. Likewise, the cost of installing a number of cupolas in such a situation is a burden. An additional objection to having a plurality of cupolas when only one is to be operated is the space required for having a number of complete cupolas all set up for operation. A foundry's conveying system is such that it is most economical and convenient to have the cupola mounted at one central position. Having the cupolas mounted for operation at scattered positions interferes with the economical and efficient distribution of materials to be charged into the cupola and with the distribution of molten metal poured from the cupola. It upsets the normal and routine operations of the foundry to have to charge one cupola at one location and then to change over to charge a cupola at another location. It likewise disturbs the normal and routine

procedure of the foundry to pour molten metal at one location and then to change over to pour it at another location. Additions and modifications in the conveying system for both raw materials and for the molten metal is necessitated by such a system of plural cupolas mounted at different locations.

It is an object of my invention to obviate the disadvantages, limitations and defects of the prior practices of foundry melting as herein suggested and as otherwise known in the art.

Another object is the provision of a flexible and adequate system for melting of metal in a cupola with the maximum of efficiency and economy.

Another object is the provision of a cupola having replaceable parts of different capacities to meet the requirements of a foundry.

Another object is the provision of a cupola having severable parts for accommodating the substitution of parts having the size and capacity required.

Another object is the provision of a cupola having a stack portion mounted in position and a plurality of well portions movable relative to the stack portions and adapted to be selectively assembled therewith.

Another object is the provision for an improved method of melting operation in a foundry.

Other objects and a fuller understanding of my invention may be had by referring to the following description and claims, taken in conjunction with the accompanying drawings, in which:

Figure 1 is an elevational view of apparatus embodying my invention;

Figure 2 is a longitudinal sectional view of the adjoining portions of the stack and well of the left-hand cupola shown in Figure 1;

Figure 3 is a longitudinal sectional view of the top of the cupola well shown on the right-hand side of Figure 1;

Figure 4 is a transverse sectional view through the line 4—4 of Figure 2;

Figure 5 is a plan view looking down on the top of the well shown in Figure 3 and in the direction of the arrows 5—5;

Figure 6 is a cross-sectional view of the apparatus embodying my invention shown in Figure 1 and taken along the line 6—6 of Figure 1;

Figure 7 is a view looking up at the bottom of a cupola well in my apparatus and is a view in the direction of the arrows 7—7 of Figure 1;

Figure 8 illustrates a modified form of carriage and track wherein intermeshing gears and a rack are utilized; and

Figure 9 is a diagrammatical view of a modified arrangement of apparatus embodying my invention.

As shown in the view of Figure 1 there is a cupola apparatus including a stack shown generally by the reference character 11, a well of one diameter and capacity shown generally by the reference character 12 and a well of smaller diameter and capacity shown generally by the reference character 13. Although for purposes of simplicity in illustration my drawings show only the well 12 and the well 13 it is to be understood that any number of required cupola walls may be utilized and embodied in my invention. For example, there may be three or four or five wells all of different diameters or different melting capacities.

The stack 11 consists of the upper portion of a usual cupola of hollow cylindrical shape. The stack 11 or upper portion of the cupola acts as a chimney for carrying off the heat and hot gases generated within the cupola and also acts as a conduit through which material is charged into the well or lower portion of the cupola. As in the usual construction, an arrester 14 is positioned above the stack 11 as shown and charging doors 15 provide an entrance through the wall of the stack for the charging of material to the interior of the cupola.

The stack 11 extends through an appropriate opening in the charging floor 21 and is supported thereon by a suitable flange mounting 38 connecting the stack 11 to the charging floor 21. The walls of the stack 11 extend downwardly to, or slightly below, the level of the charging floor 21. It is seen from the drawings, that the stack or upper portion of the cupola is suspended at an elevated position with its open bottom end disposed at or below the elevated charging floor 21.

The well or bottom portion 12 which is positioned below the stack 11 in Figure 1 has the usual construction of the lower portion of an operative cupola. A wind box 16 mounted on the side of the well or lower portion 12 is adapted to supply a blast of air from the blast main 17 into the interior of the cupola through the tuyères (not shown), the blast main 17 being in communication with a source of air supply, such as a blower, not shown in the drawings. The inlet pipe 18 as shown in dotted lines in Figure 1 and in full lines in Figure 6 provides communication between the blast main 17 and the wind box 16.

On the front side of the cupola well and near the lower portion thereof is positioned the spout mounting means 19 to which is attached the spout 20 for the discharge of molten metal upon the tapping of the cupola. Upon the opposite side or rear of the cupola and at an elevation above the metal spout 20 is located the slag spout 45 shown in the view of Figure 6.

The well 12 is mounted upon a carriage 39 having the four wheels 40. A track 41 having suitable channeled runways is supported at an elevation by the column supports 42 above the foundation or floor 43, the floor 43 being the pouring floor of the foundry where the pouring operations take place. Suitable stops 44 are provided on the track 41 to limit the movement of the carriage 39 along the track 41 beyond the extent desired.

The well 12 is distinct and separable from the stack 11. Upon the movement of the well 12 along the track 41 to the position shown in Figure 1, the well 12 substantially registers with the stack 11. To close the clearance space between the well 12 and stack 11 and to provide a joinder

between the two parts a telescoping ring or cylinder 22 is provided at the juncture or division between the stack 11 and well 12. The telescoping ring 22 is mounted to two rods 24 by means of the extensions or ears 23. The rods 24 extend up through openings in the charging floor 21 and may be pulled up or moved down by manual operation from the charging floor. To hold the weight of the ring 22 when the rods are moved to upward position the catches 25 are adapted to engage in the notches 26. The catches 25 may be released in the usual manner to permit the rods 24 to move downwardly when lowering the telescoping ring 22. A stationary ring 27 welded or otherwise secured to the upper portion of the well 12 is adapted to sealingly engage the telescoping ring 22 when lowered and to support the telescoping ring 22 when in the position of Figures 1 and 2. The detailed operation and structure of the parts at the location of the joinder between stack 11 and well 12 is shown in detail in Figure 2.

The stack 11 is lined in the usual manner with a relatively thin refractory lining 28 composed of a layer of firebrick. The refractory lining 28 is supported in position by a supporting flange or ring 29 or by any other suitable means such as studs extending into the refractory lining.

A refractory lining 32 for the well 12 is relatively thick as compared to the refractory lining 28 as the melting and generation of heat occurs in the well or lower portion of the cupola, the stack 11 merely carrying off the hot gases generated below. An iron charging ring 31 positioned upon the top of the thick refractory lining 32 forms a ledge or shelf over the thicker lining and protects the lining 32 from damage by the material charged down into the well 12 from the charging door 15. The charging ring 31 may be of one integral piece or may be made up of a plurality of segments. As seen from Figure 2, the charging ring 31 is at the upper edge of the walls of the well 12. To better seal the joint between the stack 11 and well 12, daubing 30 of plastic refractory material, such as fireclay, is plastered between the charging ring 31 and the lower edge of the refractory lining of the stack. The daubing 30 is placed in position after the stack 11 and well 12 are in alignment to the position shown in Figure 2 and may be applied by throwing handfuls of daubing through the charging door 15 down upon the charging ring 31 into the crevice or clearance space or may be otherwise applied by suitable means.

The left-hand half of Figure 1, the view of Figure 2 and the view of Figure 4 discloses that a complete operative cupola having all of the necessary parts for the usual operation of the same is provided. It is to be understood that this cupola has all of the parts necessary for successful and continued operation of the same. For purposes of simplicity of illustration it has been considered as unnecessary to show such features as the clean-out door, peep-holes, a blower and such other features as are usually associated with a complete cupola.

The well or lower portion 13 shown on the right-hand side of the views of Figures 1 and 6 and in Figures 3, 5 and 7, is substantially similar in construction to the well 12 previously described. However, the well 13 is of smaller diameter, both internally and externally, than the well 12. The capacity of the well 13 for material charged therein is substantially smaller than that of the well 12. Preferably the wind box on

the well 13 is proportionately smaller and is adapted to accommodate the requirements of the well 13. The inlet 18 is the same on both wind boxes so as to permit universal connection with the blast main 17.

The upper edge portions of wells 12 and 13 are of substantially the same diameter and to provide for this the diameter of the smaller well 13 is expanded at location 36 to flange out as shown on the right-hand side of Figure 1. By means of the flare 36, the upper edge portion of the well 13 is adapted to register with the stack 11 as the stack 11 is of a size adapted to accommodate the larger diameter well 12.

The internal structure of the well 13 at the upper edge portion thereof is somewhat modified from that of the larger size well 12 in order to provide for the differential in diameters between the top edge portion of the well 13 and the body portion of the well 13. In the well 13 a modified form of charging ring 33 is mounted in position as shown in Figures 3 and 5. The refractory lining 34 of the well 13 is protected by the charging ring 33. The diameter within the refractory lining 34 is smaller than the diameter within the refractory lining 32 of the well 12. A ring or course of firebrick or iron block 35 is positioned upon the top of the charging ring 33 as shown in Figure 3. The top edge of the well 13 as formed by the course 35 of bricks or blocks is adapted to mate with or substantially register with the lower edge portion of the stack 11.

To permit either inlet pipe 18 of the respective wells 12 and 13 to be connected with the blast main 17 a movable connection 37 is provided on the end of the blast main 17 as shown in Figure 6. By moving the connecting sleeve 37 back on the blast main 17 the inlet 18 of one well may be disconnected and upon movement of another well to the same position the inlet pipe of the substituted well may be connected to the blast main 17. Suitable gaskets are provided at the joints of the connection 37, the blast main 17 and the inlet pipes 18.

Figure 7 being a view in the direction of the arrows 7-7 of Figure 1, shows the bottom of the well 13 and the mounting of its carriage 39 on the track 41. It also illustrates the drop-bottom doors 46 provided for cleaning out the interior of the well 13. Well 12 and any other cupola wells utilized have a similar drop-bottom door and appear substantially similar to that of Figure 7 from a view looking up at the bottom thereof.

From the views of the drawings and the foregoing description it is seen that either well 12 or well 13 may be used in conjunction with the stack 11. The stack 11 is of a diameter and capacity sufficient to meet the requirements of the largest of the cupola wells used, and thus is sufficient to carry off the hot gases of the larger size cupola wells and to provide a conduit for the charging of material into the largest of the cupola wells. In the event that the requirements of the foundry suggest the desirability of using the smaller size cupola well 13 then the well 12 is disconnected by raising the telescoping ring 22 by means of the rods 24 and the blast main 17 is disconnected by means of the adjustable connection 37, and the spout 20 is removed. The well 12 is then rolled along the track 41 upon its carriage 39 to one side away from the stack 11. The smaller size well 13 is then rolled along the track 41 to the position previously occupied by the well 12 under the stack 11. The telescoping

ring 22 is lowered to join the stack 11 and well 13 and daubing may be applied as required or desired. The blast main 17 is then placed in communication with the wind box of the well 13 through its respective inlet pipe 18. The spout 20 is then mounted in pouring position to the well 13. The substituted well 13 and stack 11 then form a complete and operative cupola having a melting capacity meeting the present requirements of the foundry. It is understood, of course, that other wells of varying diameter and capacity may be used in my apparatus, only two wells 12 and 13 being shown in the views of the drawings for purposes of simplicity in illustration.

It is to be noted that the cupola well out of operation and standing at one side may be readily cooled and daubing or patching placed therein during the repair of the lining may be readily dried by reason of the free circulation of air through the interior of the well up through the opened drop-bottom door and through the open top of the disconnected well. This feature is a great advantage in the repair and rebuilding of the cupola lining, particularly of the burn-out in the lining, and greatly facilitates keeping the cupola in operation without undue loss of time.

While only a straight section of track 41 is shown in the drawings, it is to be understood that this track 41 includes sufficient length for moving the cupola wells around as desired and includes Y's or other configuration necessary for the desired switching of the cupola wells around in desired locations. Likewise, a turntable or any other suitable arrangement may be used for facilitating the movement of one well into position and the moving of the other well out of position in assembling a cupola of desired capacity.

Figure 8 illustrates a modified arrangement for moving the respective wells about as desired. In this modified arrangement gear wheels 47 are substituted for the round wheels 40 and the rack 48 is substituted for the smooth bottomed track 41. A crank handle 49 may be applied to the axle of the gear wheel 47 to move the carriage 39 along the rack 48 and to thus move the respective cupola well forward or backward relative to the stack 11.

Figure 9 illustrates diagrammatically a modified arrangement for moving a plurality of cupola wells of different diameters relative to a cupola stack. In Figure 9 there are four cupola wells of different capacities, these being wells A, B, C and D. The four wells of progressively increasing capacity are movably mounted upon a circular track denoted by the reference characters X and Y. The cupola wells A, B, C and D are movable along the circular track XY in respect to the cupola stack D' shown in broken line. The stack D' is mounted in fixed position and is of a capacity sufficient to accommodate the larger of the cupola wells which is cupola well D. In the illustration of Figure 9, cupola well C is registered with and joined with the cupola stack D' and with it forms a complete operative cupola. The cupola wells A, B and D are idle and are positioned back away from the stack D' where the melting operation takes place. The cupola wells A, B, C and D may be independently rolled around on the track XY or may be joined together in spaced relationship in which case the track XY is a turntable upon which the cupola wells revolve.

My invention includes the method of operating a foundry wherein a cupola stack is utilized for

selective combination with a plurality of cupola wells of different capacity as herein described. My invention also includes the method of, and apparatus for, mounting a complete cupola on a carriage movable on a runway, on a cupola or on other suitable moving means to utilize one tapping and pouring location in the foundry. The present specification includes the foregoing description taken in conjunction with the views of the drawings as well as the description of my invention as contained in the annexed claims which are made a part of this specification by reference thereto.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In a foundry metal melting system, a unit comprising the combination of a plurality of cupola wells having different sized diameters for meeting different metal melting requirements of the foundry, a cupola stack having a diameter sufficient to provide an adequate outlet for hot gases from the larger diameter size of said wells, said cupola stack having an open bottom and being mounted at an elevated position to permit either of said wells to be positioned below the open bottom of said stack, there being a clearance space between the bottom of the stack and the top of said either well to permit sideward movement of the well relative to the stack, each of said wells having an open top adapted to register with the open bottom of said stack, a common support for said wells, said common support being disposed on one horizontal plane, carriage means connecting said wells and said support to permit movement of said wells along said horizontal plane for interchange of said wells relative to said stack, and movable closure means suspended downwardly from said stack for closing said clearance space upon registration of either of said wells with said stack and for opening said clearance space upon sideward movement of said either well relative to the stack the arrangement of the stack, the plurality of wells, the support and the carriage means providing for the ready assembly of a stack and well cupola structure of required metal melting capacity.

2. A metal melting system for a foundry having different operating requirements wherein the respective capacities of different diameter cupolas are required for said requirements, comprising, in combination, a unit consisting of a plurality of cupola wells of different diameters for accommodating different amounts of material therein but all having top members of the same diameter, a cupola stack having a diameter sufficient to meet the requirements of the larger of said cupola wells, said cupola stack being mountable at a fixed elevated position, movable mounting means disposed on a fixed horizontal plane below said stack for said plurality of wells to permit a selected well to be moved along said plane and under said stack and in alignment therewith to provide a cupola, and joining means extensible downwardly from said stack for joining the stack and said selected well.

3. In a metal melting system for a foundry requiring different melting capacities at different

times, a cupola structure having interchangeable parts for meeting said different requirements, said cupola structure comprising a stack portion mounted at an elevation and in fixed position, a unit comprising a plurality of well portions having different melting capacities, respectively, a support disposed on a horizontal plane for said well portions, means for moving said well portions along said support laterally of said stack portion to selectively position one of said well portions under, and in juxtaposition to, said stack portion, and movable connecting means adapted to extend downwardly from said stack portion toward said selected well for joining said stack portion and said selected well portion maintained on said horizontal plane to complete said cupola structure without vertical movement of said selected well portion, the completed cupola structure being assembled to meet the melting requirement of the foundry.

4. The combination of a cupola stack of a fixed dimension, a unit comprising a plurality of cupola wells of different dimensions disposed on one horizontal plane each provided with an open top designed for interfitting with said cupola stack, the dimension of the stack being sufficient to accommodate the requirements of the largest of said wells, and carrying means for moving said wells relative to, and laterally of, said stack on said horizontal plane to provide for the selective joinder of a well of required dimension while on said horizontal plane, of said plurality of wells, to said stack in accordance with the melting capacity desired.

5. In a metal melting system of a foundry, a cupola having a stack portion and a unit comprising a plurality of well portions, said well portions being disposed along a horizontal plane below said stack portion, the stack portion having a bottom opening, and each of the well portions having a top opening adapted to register upon positioning a selected well portion immediately below the said stack portion to form a complete cupola, said well portions having different capacities to meet different melting requirements of the furnace and said stack portion having a capacity to serve the larger of said well portions, means for moving said well portions laterally of said stack portion along said horizontal plane to provide for ready replacement of one of said well portions with another of said well portions without vertical movement of said selected well portion, and telescoping means extensible downwardly from the stack portion toward the said selected well portion for connecting said stack portion to the said selected well portion placed beneath said stack portion.

6. A cupola having a stack portion and a well portion separated from each other, said stack portion being mounted independently of said well portion, said stack portion having a charging door and said well portion having a wind box and being adapted to receive substantially all of the material charged into said cupola through said door, carriage means for movably supporting said well portion to permit it to be moved laterally of the stack portion and toward and away from said stack portion, and adjustable connecting means surrounding the bottom of the stack portion and adapted to telescope the top of said well portion for joining said stack portion and said well portion to be selectively joined and disjoined without vertical movement of the well portion, the ar-

angement of stack portion, well portion, carriage means and connecting means providing for the ready substitution of another well portion for said well portion in said cupola.

7. A cupola having a stack portion and a well portion adapted to receive substantially all of the material charged into the cupola, a movable intermediate portion adapted to telescopically embrace the bottom of the stack portion and the top of the well portion for facilitating ready joinder and severance of the said stack portion and well portion, and a movable carriage for said well portion for facilitating ready movement of the well portion laterally of the stack portion and toward and away from said stack portion to provide for the assembling and dis-assembling of the stack portion and well portion without vertical movement of the well portion.

8. A cupola having a vertically movable severable intermediate portion embracing the lower portion and upper portion of the cupola to permit separation of the lower portion relative to the upper portion of the cupola and having a movable base to permit lateral movement of the lower portion relative to upper portion upon vertical movement of said intermediate portion whereby said lower portion may be replaced by another lower portion moved directly lateral of said upper portion, said lower portion being adapted to receive substantially all of the material with which the cupola is charged.

9. In a foundry having a charging floor on one level and a pouring floor on a second level below said one level and having a blast main, the combination of an upper portion of a cupola forming the stack and charging conduit of said cupola, said upper portion being mounted to said charging floor, a unit comprising a plurality of lower portions for said cupola, each said lower portion forming a well for the melting of metal and a wind box for the distribution of an air blast to the well, said wells having different sized internal diameters to accommodate different amounts of material therein, a track positioned intermediate, and parallel to, said charging floor and said pouring floor, wheeled carriages for each of said lower cupola portions movable along said track to permit movement of the said lower cupola portions under said charging floor laterally of the upper cupola portion to and from a position under said upper cupola portion, a movable connection adapted to provide communication between said blast main and the wind box of the lower cupola portion positioned below said upper cupola portion, and a movable joining member carried by said charging floor and adapted to surround and telescopically join the upper cupola portion to the lower cupola portion positioned below said upper cupola portion, the combination of upper cupola portion, lower cupola portions, track, carriages, movable connection, and movable joining member providing for the assembling of a lower cupola portion of selected capacity to the upper cupola portion to provide an operative cupola of required size in communication with said blast main.

10. In a foundry having a charging floor on one level and a pouring floor on a second level below said one level and having a blast main, the combination of an upper portion of a cupola forming the stack and charging conduit of said cupola, said upper portion being mounted to said charging floor, a lower portion for said cupola forming a well for the melting of metal and a wind box for the distribution of an air blast to the well, a track positioned intermediate, and parallel to, said charging floor and said pouring floor, a wheeled carriage for said lower cupola portion movable along said track to permit movement of the said lower cupola portion under said charging floor laterally of the upper cupola portion to and from a position under said upper cupola portion, a movable connection adapted to provide communication between said blast main and the wind box of the lower cupola portion when positioned below said upper cupola portion, and a movable joining member carried by said charging floor and adapted to surround and telescopically join the upper cupola portion to said lower cupola portion, the combination of upper cupola portion, lower cupola portion, track, carriage, movable connection, and movable joining member providing for the ready assembly and dis-assembly of a complete cupola to provide as required an operative cupola in communication with said blast main.
11. A cupola comprising an upper section having a charging door and adapted to carry off hot gases generated in the operation of the cupola, a lower section having a wind box and adapted to receive substantially all of the material charged into the cupola through said charging door, fixed support for said upper section, means for supporting said lower section for movement in a horizontal direction, and means for detachably connecting said sections together.
12. A cupola comprising an upper section adapted to carry off hot gases generated in the operation of the cupola, a lower section adapted to contain substantially the entire charge of the cupola, separate supports for said upper and lower section, one of said sections being movable horizontally with respect to the other, and means for detachably connecting said sections together.
13. A cupola comprising an upper section adapted to carry off hot gases generated in the operation of the cupola, a unit comprising a plurality of lower sections having different melting capacities, each section being arranged for selective vertical alignment with the upper section, a first support for the upper section, a second support for the lower sections, one of said supports being movable horizontally with respect to the other to vertically align a lower section with the upper section to make a complete cupola with the lower aligned section adapted to contain substantially the entire charge of the cupola, and a movable interconnecting means for interconnecting a vertically aligned lower section and the upper section, said movable interconnecting means being adapted to fit all of the lower sections.

HERBERT A. REECE.
